UNITED STATES PATENT OFFICE.

CHARLES F. MILLER, OF MOORE, PENNSYLVANIA, ASSIGNOR TO WESTINGHOUSE ELECTRIC AND MANUFACTURING COMPANY, A CORPORATION OF PENNSYLVANIA.

INDUSTRIAL STOKER.

Application filed December 21, 1923. Serial No. 682,131.

My invention relates to industrial stokers of the type wherein fuel is introduced through a main retort extending from the front toward the back of the stoker and spreads out from said retort over one or more sloping grate surfaces extending from the margin or margins thereof, and it has for its object to provide apparatus of the character designated which shall be effective to burn fuels of varying character and grades efficiently and without clogging.

A further object of my invention is to provide a dumping mechanism for a stoker of the character above described which shall serve to dump the refuse at will while, at the same time, preventing avalanching of the fuel bed.

In the accompanying drawing, Fig. 1 is a fragmentary plan view of a stoker constructed in accordance with my invention; Fig. 2 is a sectional view of the structure shown in Fig. 1 taken along the plane II-II in Fig. 1; Fig. 3 is a side view of a tuyère bank, together with associated operating mechanism as may be employed in the structure of Fig. 1, the view being taken on some such plane as that indicated at III-III in Fig. 1; Fig. 4 is a detail view of a mechanical movement employed in the structure of Fig. 1 to translate the reciprocatory movement of the main ram drive to oscillating movement of a shaft suitable for actuation of grate members as will herein-after more fully appear; Fig. 5 is a side view of the structure shown in Fig. 1, being taken along the plane indicated at V-V; Fig. 6 is a detail view of the dump grate mounting; Fig. 7 is a plan view of the same; and Fig. 8 is a detailed view showing a modified form of tuyère bank operating mechanism similar to that shown in Fig. 3.

In the operation of so-called industrial boilers as are employed for the heating of public buildings and in small manufacturing plants, it is desirable to employ a mechanical stoker of relatively small capacity as compared with the so-called multi-retort underfeed stoker and which shall furthermore require much less height of fire box than is necessary for the multi-retort underfeed stoker.

With these and other objects in view, I provide a stoker in which a main retort extends rearwardly from the front wall in a substantially horizontal direction but little

above the floor of the fire box, and I force fuel thereinto from a hopper of the usual type by means of a main ram and, if desired, by auxiliary rams disposed within the retort.

Said retort has substantially continuous sides, and sloping away from one or both of the margins thereof I provide a grate surface, the inclination being such as to promote lateral movement of the fuel from the retort without avalanching thereof. This grate surface is preferably formed of tuyère banks alternating with moving fuel rams, hereinafter designated as lateral rams, said rams and tuyères lying in substantially the same plane. If desired, the tuyère banks themselves may also be capable of movement. At the foot of the grate surface or surfaces thus provided, I may provide a dump plate normally occupying a substantially horizontal position, but susceptible of bodily motion toward the grate, while at the same time elevating the edge thereof adjacent to the grate, whereby refuse supported thereupon is dumped away from the grate and at the same time, said up-raised edge effectively prevents the avalanching of the fuel bed.

Referring to the drawing for a more detailed understanding of my invention, I show the front wall of a fire box at 10 in Figs. 1 and 5. Disposed in front of this wall is a hopper 11 of usual form discharging into a ram box 12.

A steam cylinder 13 is provided in front of the hopper 11 and a piston therein contained is directly connected with a main fuel ram 14 and, if desired, auxiliary fuel rams 15 and 16 within the fire box may also be driven directly from the steam cylinder 13 as through a rod 17.

The specific nature of the steam operating mechanism 13 forms no part of the present invention, but a preferred form is illustrated and claimed in my co-pending application Serial No. 663,436, filed Sept. 18, 1923, Patent Number 1,624,004 and assigned to the Westinghouse Electric and Manufacturing Company. Suffice to say, by means of suitable valve mechanism 18, the steam cylinder 13 may be caused to operate the main fuel ram at any desired speed within the range of capacity of the stoker in question.

Projecting inwardly from the ram box 12

is a main retort 19 extending to the back of the stoker as indicated at 20 and preferably having its bottom substantially horizontal throughout its length except for an upward 5 inclination of the bottom at the rear as indicated at 21. The main retort structure is supported relatively close to the floor of the fire box, as by suitable supports 22-22.

As indicated in Fig. 2, the side of the 10 main retort 19 is formed by a plate 23-23 surmounted by castings 24 alternating with castings 25, the respective arrangement of these latter castings being more clearly shown in Fig. 5. It will be noted that the 15 upper edge of the side wall thus formed is an approximately continuous unbroken line so that all fuel introduced into the main retort is forced to ascend up over said side wall before reaching other parts of the 20 stoker.

Sloping away from the retort margin thus formed is a grate surface embodying tuyère banks 26-26 with intervening lateral fuel rams 27-27, these elements coacting to provide 25 an approximately flat grate surface inasmuch as the upper surfaces of the rams 27-27 lie substantially in the plane of the tuyères 26-26.

The rams 27-27 are arranged for lateral 30 movement in order to insure fuel passage toward the lower edge of the grate surface and, to this end, they are mounted in curved seats 28-28 as clearly shown in Fig. 2, these seats being indicated as concaving upward 35 and having substantially a uniform radius.

A shaft 29 extends through beneath the grate surface and is arranged to be oscillated by the reciprocation of the main ram as by a link and bevel gear connection indicated in Fig. 4. This specific connection forms no part of the present invention but is separately described and claimed in my co-pending application Serial No. 631,661, filed April 12, 1923, Patent No. 1,657,224 40 and assigned to the Westinghouse Electric 45 and Manufacturing Company. Suffice to say, a connection 30 on the main ram swings a link 31 provided with an arcuate slot 32, the further end 33 of the link 31 being 50 pivoted on a crank arm 34 movable about a fixed center 35. A crank arm 36 is also movable about the center 35 and is connected on the one hand through a link 37 to a pin 38 in the slot 32, and is connected, on the other hand, to a portion of a beveled gear 39 meshing with a similar portion of a beveled gear 40 mounted upon the end of the shaft 29. Thus, by reciprocation of the member 30, the arc member 31 swings and moves 55 laterally in space, oscillating the bevel gear 39 through the link 37 with consequent oscillation of the shaft 29. A screw 70 determines the location of the pin 38 in the slot 32, moving said pin toward the floating pivot 33 shortening the degree of oscillation 60 65

of the shaft 29 with a given motion of the main ram and vice versa.

Obviously any other suitable form of mechanical movement may be employed for translating said reciprocating driving motion into said oscillatory driven motion. 70

Where the shaft 29 passes beneath the lateral rams 27, it is provided with a gear portion 41 meshing with a rack member 42 pivotally connected to the respective upper 75 rams 27 and also connected through a link 43 with the lower rams 27. Thus, by oscillation of the shaft 29, the rams 27-27 are given a to-and-fro motion on their curved seats, the result of the specific arrangement 80 thus described being that the motion of said rams is a combination of reciprocation and tilting, inasmuch as at the upper limit of motion, the upper ends of the rams are thrown up, and at the lower limit of travel 85 the lower edges are thrown up. By virtue of this specific motion, not only is the fuel fed downwardly over the grate surface, but also is raised and lowered, breaking up the partially fused mass to enable the air to 90 pass freely therethrough and also serving to free the tuyère openings in the ram members 27-27 so as to permit the ready escape of air therefrom.

This last-named function of the rams 95 27-27 is of considerable importance, these rams being formed of tuyère members 44-44 with air openings 45 at the lower edges thereof so as to permit the free flow 100 of air thereinto.

With certain types of fuel and conditions of the fuel bed, the structure thus described to this point functions satisfactorily with the tuyère banks 26-26 fixed in position. I find, however, that with certain types of fuel, more particularly those types wherein cooking tends to provide a strongly cohesive mass, arching may take place from one tuyère bank to the next so that the lateral rams are ineffectual. To obviate this action, 105 I may arrange the tuyère banks 26-26 for reciprocation as indicated in Fig. 3. The respective tuyères are mounted on a plate 46 so arranged that air may pass readily therethrough, and this plate is provided with a 110 depending arm or lug 47 extending down to a plane below that of the shaft 29. The arm 47 is provided with a pivotal opening 48 disposed above the shaft 29 and with a similar pivotal opening 49 disposed below 115 the shaft 29. A crank arm 50 is clamped upon the shaft 29 and is connected to the pivotal point 49 as by a link 51. Thus, the oscillatory motion of the shaft 29 causes reciprocation of the tuyère bank 26 upon 120 supports 52 and 53.

It will be noted that inasmuch as the lateral rams 27-27 are driven from the upper side of the shaft 29, whereas the tuyères 26 are driven from the lower side of the shaft 125 130

29, there is a marked difference in phase between the motions of the two elements, that is to say, the tuyères 26 are moving upwardly while the lateral rams 27-27 are 5 moving downwardly and vice versa, thus providing a very effectual movement of the fuel bed under all conditions.

If it be desired that the fuel bed be not agitated as violently as is the case with this 10 construction, the crank arm 50 may be unclamped from the shaft 29 and swung to such a position that the crank arms projects above said shaft, as shown in Fig. 8. The link 51 is then connected in the pivotal opening 48 and, under these conditions, the movement of the tuyères 26-26 is substantially 15 in phase with the movement of the lateral rams 27-27, although the range of movement is, in general, not the same, so that 20 there is still a slight shearing action tending to keep the fuel bed in a broken-up condition.

By adjustment of the screw 70, the stroke 25 of the lateral rams and of the tuyères may be altered with a fixed stroke of the main ram, thus hastening or slowing up the rate 30 of fuel travel over the lateral grate to accord with the rate of fuel introduction by the main ram and to modify the shape of the fuel bed.

Disposed at the lower edge of the inclined grate surface is a dump plate 55 made up of suitable plate elements, and this dump plate is carried on a transversely-extending shaft 35 56 supported at its ends in suitable rollers, one of which is shown at 57 in Figs. 6 and 7. Each of these rollers is carried on a track member 58-59, preferably encased within the furnace wall so as to shield the 40 roller from heat and also to protect it from dust and dirt.

A dumping shaft 60 extends transversely of the lateral grate beneath the lower edge thereof and may be oscillated as through a 45 handle 61. Links 62 are attached to the shaft 56 on the one hand, and to the ends of crank arms 63 mounted on the shaft 60 on the other hand, so that oscillation of the shaft 60 tends to cause bodily translation of 50 the entire dump plate structure to and from the sloping grate, this movement being permitted by movement of the rollers 57 on the tracks 58-59.

Additional crank arms 64 are also carried 55 by the shaft 60 and engage the dump plate 55 near the edge thereof adjacent to the lower edge of the grate surface. Thus, in the position shown in full lines in Fig. 2, the dump plate is substantially in the normal 60 position, closing the dumping opening and adapted for the reception of refuse. Movement of the handle 61 in a clockwise direction tends to move the dump plate toward the grate but, at the same time, the 65 arms 64 throw up the right-hand edge of the

dump plate 55 so that it clears the lower edge of the grate and in the dumping position, indicated roughly in dotted lines at 65, it will be noted that this upturned edge projects sufficiently above the lower edge of the 70 grate to prevent avalanching of the fuel.

As is common with stokers of this type, air under pressure may be supplied beneath the entire grate surface, this air passing through the tuyère opening in the tuyère 75 bank 26 and also through the openings in the lateral rams and through suitable side wall tuyères, if desired, whereby effectiveness and flexibility of operation may be secured. 80

From all the foregoing, the operation of the device will be obvious. Coal is fed into the hopper 11, forced into the main retort by the rams 14, 15 and 16 and is there largely coked. The resultant mass rises up out of 85 the main retort, pouring over the retort margin down upon the lateral grate where it is supplied with an abundant amount of air to insure complete combustion, a uniform progressive movement being imparted thereto by the reciprocation of the tuyères 26 and of the lateral rams 27. The refuse accumulating upon the dump plate may be discharged at will by the operator without 90 material disturbance of the fuel bed, because 95 of the advantageous damming action of the up-raised action of the dump plate during the dumping operation.

If greater capacity is desired, a similar inclined grate surface may be provided sloping away from the other margin of the main 100 retort.

While I have shown my invention in but one form, it will be obvious to those skilled in the art that it is not so limited, but is 105 susceptible of various other changes and modifications, without departing from the spirit thereof, and I desire, therefore, that only such limitations shall be placed thereupon as are imposed by the prior art or as 110 are specifically set forth in the appended claims.

What I claim is:—

1. In a mechanical stoker, the combination with a longitudinally extending retort 115 having means for introducing fuel thereto, of an overfeed grate surface extending laterally and downwardly from an upper margin of the retort and comprising alternately arranged tuyère banks and fuel feeding means, said fuel feeding means including curved seats extending laterally with respect to the retort and rams mounted to reciprocate therein, and mechanism for moving said rams upon said seats laterally with 120 respect to the retort.

2. In a mechanical stoker, the combination with a longitudinally extending retort 125 having means for introducing fuel thereto, of an overfeed grate surface extending lat- 130

erally and downwardly from an upper margin of the retort and comprising alternately arranged tuyère banks and fuel feeding means, each of the fuel feeding means including a concave supporting surface extending laterally with respect to the retort and a ram slidably mounted on said concave supporting surface, and mechanism for moving said rams laterally with respect to said retort whereby a combined reciprocatory and tilting motion is imparted to each ram.

3. In a mechanical stoker, the combination with a longitudinally extending retort having means for introducing fuel thereinto, of an overfeed grate surface extending later-

ally and downwardly from an upper margin of the retort and comprising alternately arranged tuyère banks and fuel feeding means, each of said fuel feeding means including a pair of concave supporting surfaces extending laterally with respect to said retort and arranged in end to end relation and a ram slidably mounted on each of the concave supporting surfaces, and mechanism for moving the rams laterally with respect to said retort.

In testimony whereof, I have hereunto subscribed my name this 20th day of December, 1923.

CHARLES F. MILLER.
